UNITED STATES PATENT OFFICE.

CHARLES ELWOOD KEAS, OF LOS ANGELES, CALIFORNIA.

DOUBLE-ACTING ENGINE.

Application filed February 21, 1923. Serial No. 620,478.

My invention relates to that type of double acting engine in which there is an explosion in each end of the cylinder, and the object of my invention is to provide such an engine which will be practical, simple and economical and which will be more efficient than anything of the character yet produced.

Other objects of my invention are to provide in an engine of the character referred to a construction in which the friction is reduced to a minimum in the cylinders by providing a moving sleeve in the cylinder in which the piston moves, with means for moving said sleeve in the same direction with the piston, but at a slower speed; to provide a construction in which the cylinders are separated from the crank case, thus avoiding any possible pumping of oil into the cylinders and the consequent forming of carbon therein; to provide a double piston in each cylinder, with connecting means outside of the cylinder, the pistons of two cylinders being preferably connected to the same connecting rod; to provide means from the same crank which is connected to the pistons for connecting to and operating the sleeves in said cylinders; to provide a construction and arrangement of double acting engine which will permit of a shorter cylinder and be of less weight than the standard motor of the single acting type. Other advantages will be apparent from the following description of one practical embodiment of my invention, taken in connection with the accompanying sheet of drawings. In the drawings,

Figure 1 is a transverse vertical sectional view through an engine embodying my invention;

Figure 2 is a similar view at right angles to the view in Fig. 1; and Figure 3 is a cross sectional view on line 3—3, of Fig. 2.

Referring more in detail to the drawings, I have shown one unit of two cylinders for purposes of description, but it is to be understood that any number of units can be used together, as may be desired.

In the drawings, 1, designates a cylinder block, with two cylinders, 2 and 3, therein, and with the water jackets, 4, 4, formed around portions of the cylinder. Between the cylinders is an open space 5, and at the opposite outer sides, the walls of the cylinders are provided with longitudinally extending slots, 6, with side plates of sheet

metal, as 7, 7, mounted over said slots, at a space therefrom, substantially as shown. The cylinders have both ends closed, as indicated, and at the lower end of the cylinder block is a crank case, 8, with a crank shaft, 9, mounted therein, said crank shaft having the longer crank arms, 9^a, 9^a, and the shorter crank arms, 9^b, 9^b, with the bearings, 9^c, 9^c, and 9^d.

Mounted in the cylinders are two double pistons, 10, 10, there being two pistons in each cylinder, connected by a cross-like tie rod, 11, through which extends a wrist pin 12, said wrist pin 12 extending through from one cylinder to the other, through the slots in the sides of the cylinders, as clearly indicated in Fig. 2. The outer ends of said wrist pin are connected by means of connecting rods, 13, 13, with the bearings 9^c, 9^c, of the crank 9, in the crank case. Mounted within each cylinder, around the pistons, is a sleeve, 14, also having in its opposite sides short slots, 14^a, 14^a, through which the wrist pin 12 works, as will be clear from Fig. 2. Each sleeve 14, is provided inside with a bearing lug 14^b, with a wrist pin 15, extending from one sleeve to the other, through the slots, 14^a, 14^a. A connecting rod, 16, connects said wrist pin 15 with the bearing 9^d of the crank 9. It will be noted that the connecting rod 16, which connects the sleeves, 14, 14 with the crank, 9, has only about half the movement of the connecting rods 13, 13, and that they move the sleeves 14, 14, only about half the distance traveled by the pistons, and at about half the speed, and in the same direction. The purpose of the sleeves is to cover up the slots in the sides of the pistons. This construction enables me to use much shorter pistons and cylinders. The sleeve also cuts the surface speed of the piston in half since it moves in the same direction with the piston moving therein. The usual poppet valves 17, 17, are provided substantially as shown, operated by means of a cam shaft, 18 and cam 19, with springs, 20, 20, normally closing said valves, as will be clear from the showing made. These valves are arranged in pairs in the usual manner to govern the intake and exhaust, and are properly timed as to their operation, but as this is well known construction, need not be made detailed as to showing and description.

The operation of the engine will be clear from the showing made and the description

thereof; but attention is called to the fact that when an explosion is taking place in one end of a cylinder, a compression is taking place in the other, while in the other cylinder of each pair an intake is taking place in one end and an exhaust is taking place in the other end thereof. It is understood, of course, that a four cycle motor is described. The cycle of the cylinders may be stated as follows, to-wit—upper left cylinder: explosion, exhaust, intake and compression. Lower left cylinder: compression, explosion, exhaust and intake. Upper right cylinder: intake, compression, explosion and exhaust. Lower right cylinder: exhaust, intake, compression, and explosion.

I do not limit my invention to the details of construction and arrangement here shown for purposes of illustration, except as I may be limited by the hereto claims, knowing that many changes can be made therein without departing from the spirit of the invention.

I claim:

- 25 1. In an engine of the character referred to, in combination, two pairs of cylinders, each pair being side by side and the cylinders of one pair being in axial alinement with the cylinders of the other pair, two 30 pairs of double pistons, a single wrist pin between the upper and lower pistons and with which said pistons are connected whereby all move together as a unit, said pistons moving within said cylinders, respectively, 35 a crank, and operating connections from the outside opposite ends of said wrist pin to said crank.
- 40 2. In an engine, in combination a cylinder block having two cylinders at each end thereof, two double pistons, a wrist pin between the upper and lower pistons and connections from said double pistons to said wrist pin, whereby said wrist pin and said four pistons move together as a unit, a 45 crank case and crank therein, connections from the opposite ends of said wrist pin to said crank, and inlet and exhaust valve mechanism for controlling the intake and exhaust from said cylinders.
- 50 3. In an engine of the character referred to, a pair of cylinders, double pistons in each cylinder, a wrist pin connection through the sides of the cylinders to said pistons, a crank case and crank, a connecting rod from said wrist pin to said crank, whereby said double 55 pistons in both cylinders move as a unit with said connecting rod and said crank, and a sleeve in each cylinder, within which the pistons move, said sleeve moving with the 60 pistons and in the same direction.
- 65 4. In an engine of the character referred to, a pair of cylinders, double pistons in each cylinder, a wrist pin connection through the sides of the cylinders to said 70 pistons, a crank case and crank, a connect-

ing rod from said wrist pin to said crank, a sleeve in each cylinder within which the pistons therein move, a connecting rod from said crank to said sleeve for moving said sleeve with the pistons, and means for connecting said rods through the sides of the cylinders and said sleeves to said pistons and said sleeves, substantially as described.

5. In an engine of the character described, in combination, two cylinders closed at their opposite ends, double pistons therein, means connecting the pistons of both cylinders together through slots in the sides of said cylinders, a crank case and crank therein, connecting rods from said crank to the connecting means of said pistons, sleeves in said cylinders and around said pistons, and means for moving said sleeves with said pistons.

6. In an engine of the character described, a cylinder having both ends closed and having slots through its opposite sides, a sleeve sliding within said cylinder to cover said slots which said sleeve does not act as a valve, a piston within said sleeve, a crank case and crank therein, a connecting rod from said crank and attached through said slots in said cylinder wall and through said sleeve to said piston, valve-controlled inlet and outlet openings to both ends of said cylinder, and means whereby said sleeve is caused to move with said piston and in the same direction.

7. In an engine of the character described, two cylinders side by side with their both ends closed and having slots through their sides, sleeves in said cylinders to cover said slots, pistons in said sleeves in said cylinders, a crank outside of said cylinders, a connecting rod from said crank and connected through the slots in said cylinders to said pistons, a connecting rod from said crank to said sleeves for moving them with said pistons, and means whereby the sleeves are moved in the same direction a less distance and at a slower speed than said pistons, substantially as described.

8. In an engine, in combination, a cylinder block with two cylinders therein having both ends closed and having slots through their sides and having a space therebetween, a sleeve in each cylinder to cover said slots, a piston in each cylinder, within said sleeve, a wrist pin connection from one piston, through said slots to the other piston, a crank, a connecting rod from said crank to said wrist pin, a connecting rod from said crank to said sleeves, and means whereby said sleeves and said pistons are moved together at different speeds, in the same directions and for different distances, and valve controlled inlet and exhaust openings from the opposite ends of said cylinders, substantially as shown and described.

9. In an engine, in combination, two cyl-

- inders mounted together and each having both ends closed and having slots through its sides, a sleeve in each cylinder to cover said slots, a double piston in each sleeve, a connecting wrist pin through said cylinders from one piston to the other, connecting rods from said wrist pin at the opposite sides of said cylinders, a connecting rod from said sleeves and between said cylinders, a crank, 5 said connecting rods being connected to said crank, said crank being adapted to drive said pistons and sleeves at different speeds in the same direction and valve-controlled inlet and exhaust openings in said cylinders.
- 10 15 10. In an engine, in combination, a cylinder having longitudinally extending slots in its sides, a double piston therein, a moving sleeve interposed between said piston and said cylinder and within which said piston moves, crank connecting rods connected through said slots in the cylinder and through the wall of said sleeve to said pis-
- ton, a crank, and connections for moving the sleeve in the same direction with the movement of the piston, said connections for moving the sleeve being from the crank and moving more slowly. 25
11. In an engine, in combination, a cylinder having slots through its side extending longitudinally thereof, a sleeve sliding within said cylinder to cover said slots, a double piston within said sleeve and movable therein, a crank, and connections from said crank to said double piston and to said sleeve whereby the same are moved at different 30 speeds in the same direction and for different distances, and valve controlled inlets and outlets at the opposite ends of said cylinder and independent of said sleeve. 35

Signed at Los Angeles, Los Angeles County, California, this 15th day of February, 1923.

CHARLES ELWOOD KEAS.
